(57) **CLAIM**

The ornamental design for a paper plate with fluted edges, as shown and described.

DESCRIPTION

FIG. 1 is a perspective view of the paper plate with fluted edges;

FIG. 2 is a top plan view of invention shown in FIG. 1;
FIG. 3 is a bottom plan view thereof; and,
FIG. 4 is a side elevational view thereof.

The features shown in broken lines depict environmental subject matter only and form no part of the claimed design.
